(57) **CLAIM**

The ornamental design for a deflector for sprinkler head as shown and described.

DESCRIPTION

FIG. 1 is a rear elevational view of a deflector for sprinkler head showing my new design;

FIG. 2 is a front elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a rear, bottom, and right perspective view thereof;

FIG. 8 is a front, bottom, and left perspective view thereof; and,

FIG. 9 is a front, top, and right perspective view of an arm plate of the deflector, the main body of the deflector being omitted.

The broken line in the drawings is included for the purpose of illustrating environment and forms no part of the claimed design.

The dash-dot line represents the boundary of the claimed design.

1 Claim, 9 Drawing Sheets
